UNITED STATES PATENT OFFICE.

ADDISON JENKINS, OF KOKOMO, INDIANA, ASSIGNOR TO D. C. JENKINS GLASS COMPANY, OF KOKOMO, INDIANA, A CORPORATION.

DESIGN FOR A GLASS JAR OR SIMILAR CONTAINER.

Application filed July 18, 1927. Serial No. 22,800. Term of patent 7 years.

To all whom it may concern:

Be it known that I, ADDISON JENKINS, a citizen of the United States, and a resident of the city of Kokomo, county of Howard, and State of Indiana, have invented a new, original, and ornamental Design for a Glass Jar or Similar Container, of which the following is a specification, reference being had to the accompanying drawings, forming a part thereof.

In the drawings, Fig. 1 is an end elevation of the glass jar or similar container. Fig. 2 is a side elevation thereof. Fig. 3 is a plan view.

I claim:

The ornamental design for a glass jar or similar container, as shown.

ADDISON JENKINS.
